BUILDER MOTION FOR RING, CAP OR FLYER SPINNING, TWISTING, AND ANALOGOUS MACHINES

Application filed December 5, 1931, Serial No. 579,286, and in Great Britain November 11, 1931.

This invention relates to builder motions for ring, cap, or flyer spinning, twisting and analogous machines, and it has for its object to secure more efficient and perfect winding of tubes or spools of the kind employed in looms having automatic spool-changing mechanism.

It is well-known that for use in such looms the tubes or spools must be wrapped with a preliminary winding or "bunch" of yarn, of any length from two to ten yards, which must be wrapped on, at the extreme base of the spool, before actual spool building commences, and which requires an extremely short traverse or pick.

The accurate positioning of the bunch is obviously important, as with any irregularity the operation of the loom will be affected.

The control of the length of yarn wrapped on to the bunch is equally important in that too much yarn causes excessive waste and too little yarn reduces the efficient control of the loom. Finally, the shortness of the pick is an essential since, without it, the yarn tends to pile up and is very difficult to unwrap.

This invention aims to satisfy all these three essential features in a more efficient manner than hitherto.

According to the invention, the builder motion of a spinning or analogous machine of the kind referred to is so constructed that the "bunch" is built at the base of the spool irrespective of the angular position or setting of the builder motion cam when the frame is stopped, and is also so constructed that the standard pick of the builder motion is converted to the short pick requisite for building the bunch, automatically, for the full period of the bunch building operation, and means are provided whereby a selected predetermined length of yarn unaltered by any change in the counts of yarn or in the speed of the lifter motion, is automatically delivered and wrapped on to the bunch.

To this end, means are employed whereby to disconnect the builder motion cam from the chain rod when the frame is stopped, the builder motion is fitted with a pick-reducing linkage between it and the chain rod, and a manually-set automatically operating deliv-

ery regulator co-operating actuatingly with the front rollers of the machine controls a spring motor operatively associated with the rod end iron assembly.

For ring frames, in which the lifter rail rises as the bobbins are being filled, the invention embodies one constructional form, while for cap, or flyer frames, in which the lifter rail lowers as the bobbins are being filled, the invention comprises a different constructional form; both of which forms, however, operating in a fundamentally similar manner.

As one example of the application of the invention to a frame of the ring type, the short lever of the builder motion is provided, above its fulcrum, with an integral forwardly inclined extension whereof the upper end is slotted to receive a wrist pin which engages the slotted upper end of a downwardly projecting lever fulcrumed at the centre of its length to an upward extension formed on a front stationary guide plate; the lower extremity of said slotted and downwardly projecting lever being adapted to contact at a certain period with a roller, for action during the bunch pick, mounted on the end of the chain rod, and said downwardly projecting lever being oscillated by the short lever which is provided with a roller in contact with the heart cam in the usual manner.

The chain rod is provided with a supplementary roller, for action during spool building, carried by a plate which can be bolted in the appropriate position to the chain rod, which supplementary roller is adapted to be engaged by a member forming part of the rod end iron assembly.

This rod end iron assembly embodies the usual motion beam upon which the assembly is slidably supported and also comprises a depending slide formed with upper and lower lugs bored to receive a vertical stationary rod whereon is slidably mounted the rod end iron proper which is adapted to co-act with the aforesaid supplementary roller during spinning.

This vertically slidable rod end iron proper is formed on its active face with a tapered upper surface below which the surface is vertical (i. e. parallel to the axis of the station-

55

60

65

70

75

80

85

90

95

100

ary rod), while rearwardly of said surfaces the rod end iron proper is constructed with a vertical rack with which there engages a pinion carried by an arbor supported in a bearing formed in a depending extension of the aforesaid first mentioned bracket or slide. This arbor, upon which is also keyed a cam, extends forwardly of the frame and is fitted with a handwheel.

10 At or near its rear bottom end the rod end iron proper has an integral right angled projection below which is mounted a cushioning spring held in position by a vertical stem.

15 Actuatively connected to said pinion is a clock spring, and a detent pivoted to said bracket or slide is adapted to engage with the cam on the pinion shaft, the free end of said detent being attached to a wire or analogous flexible control leading therefrom to the 20 aforesaid delivery regulator.

This delivery regulator is preferably mounted adjacent one end of the lower front roller spindle which is extended through the frame end into a casing or bracket attached thereto and has formed on it or carries a worm engaging with a worm wheel keyed upon a spindle supported in a bearing formed in the aforesaid casing or bracket. A stud projecting from the casing or bracket, below 30 said spindle, carries an angularly movable lever whereof the lower end is connected by a wire, or analogous flexible connection, to the aforesaid detent engaging the cam on the rod end iron assembly, while the upper end 35 of said angularly movable lever is disposed in the path of movement of a stud carried by said worm wheel.

On the worm wheel spindle, outside said casing, is loosely mounted a disc whereof the 40 outer face is graduated in terms of yards, said disc also being apertured to engage a pin or stud projecting into said casing or bracket; and, also on said worm wheel spindle there are mounted, a pointer which is movable over 45 the subdivided face of said disc, and a knurled nut to clamp the pointer in a selected position.

The worm wheel spindle is movable axially in its bearing and is provided with a concentrically arranged return spring located between the worm wheel and the bearing.

This delivery regulator, it will thus be seen, co-operates actuatively with the front rollers of the frame and also with the rod end iron assembly.

55 In the application of the invention to a frame of the cap or the flyer type, there are certain constructional differences.

The short lever of the builder motion is not extended and does not carry the slotted lever above described, but the equivalent of such slotted lever is constituted by a bent lever carried pivotally by a vertically slidable rack member forming part of the rod end iron assembly, which bent lever carries a 60 roller adapted to engage a stationary inclined

stop or plate fixed to the upper rail of the frame; said lever being movable angularly to contact with a rounded lug (the equivalent of the roller for action during the bunch pick previously described) formed on the end of the chain rod which also carries a second rounded lug for action during spinning by contact with an adjustable stop or screw taking into a lug on the rod end iron at its forward upper end.

70 The aforesaid vertically slidable rack member is supported by a stationary rod carried by lugs projecting from the rod end iron, and the rack engages a pinion mounted on an arbor carried by the rod end iron to which arbor is anchored a clock spring as before. A cam is also keyed upon said arbor and is engaged by a detent connected by a wire or like flexible control with a delivery regulator, as 75 previously described, and a second pinion, keyed on the rear or inner end of said arbor engages a pinion keyed on a spindle carried in a bearing formed on the lower end of the rod end iron, the spindle being provided forwardly with an operating handwheel.

80 The invention is illustrated by way of example in the accompanying drawings, wherein a portion only of a frame is shown and much matter is omitted for the sake of clearness.

85 Figures 1 to 4 inclusive show the construction applicable to a ring spinning frame; Figure 1 being a front view of part of the builder-motion end of the frame, the parts being in the positions occupied during the 90 building of the bunch.

95 Figure 2 is a plan view of Figure 1 but omitting certain elements.

100 Figure 3 is a view similar to Figure 1 showing the parts in the positions occupied during the ordinary build of the bobbin; and Figure 4 is a detail view, from the rear of the builder motion.

105 Figures 5 and 6 illustrate the delivery regulator, Figure 5 being a front elevation showing part of the upper portion of the machine frame, a portion of a roller stand and of the roller shaft, and Figure 6 being an end view of the same looking towards the end-stand of the frame.

110 Figures 7 to 10 inclusive illustrate an application of the invention to a cap or a flyer spinning or like machine; Figure 7 being a view similar to Figure 1, Figure 8 a view similar to Figure 2, and Figure 9 a view similar to Figure 3. Figure 10 is a sectional end view of the rod end iron assembly and associated parts viewed from the direction of the left hand end-stand of the frame.

115 Referring firstly to Figures 1 to 4 inclusive.

120 1 is the upper part of the frame end in which is supported the lower front roller shaft 2 whereon are mounted the lower front rollers 3, and 4 is the lower or main end-stand to which are fixed the bottom rail 5 and 125

top rail 6. 7 is the ring rail and 8 are the spindles.

9 is the chain rod which is connected in the usual manner (not shown) to the ring plate 5 lifter spindles, such as 7A, and at its left hand end the chain rod 9 carries a roller 10 (for action during bunch building) with which is adapted to contact the downwardly projecting lever 11, the upper end of which is slotted 10 at 11A.

This lever 11 is fulcrumed at 12 to an upward extension 12A of the guide plate 12B. 13 is the short lever of the builder motion which is formed integrally with an upward extension 13A above the pivotal axis 13B of the short lever near the lower end of which is a roller 13C engaged by the cam 14 from which the lever 13 receives oscillatory motion in the usual manner.

20 The slot 11A in lever 11 is engaged by a wrist pin 15 which also passes through a slot 13D (Figure 3) in the extension 13A and is fitted with a nut 15A.

16 is the usual long lever of the builder motion pivoted at 16A to an extension 17 of the motion beam, and 18 is the usual screw-threaded shaft rotated by sleeve 18A and collar 18B having setscrew 18C which permits sliding movement of shaft 18 without rotation thereof if desired and as is known, 18D is the usual handwheel connected with sleeve 18A, and 19 is the usual nut connecting the top of the long lever 16 with the screwed shaft 18.

25 20 is the supplementary roller (for action during spool building) carried by the forked plate 21 bolted at 21A to the underside of the chain rod 9.

Below this supplementary roller 20 is 40 located the vertically slidable member 22 forming part of the rod end iron assembly and having an upwardly projecting inclined surface 22A adapted to contact with the roller 20. The member 22 is also formed integrally with guide bosses 22B, 22B, and with a vertical rack 23 with which a pinion 24 meshes.

25, 26, are slideways formed on the usual motion beam 27 upon which works the slide 28 integrally with which are forwardly projecting lugs 28A, 28B, which are bored to receive the vertical stationary rod 29 over which the bosses 22B, 22B, of member 22 fit slidably. The slide 28 is also formed integrally with bosses 28C, 28D, constituting bearings for the arbor 30 on which are keyed the pinion 24, the handwheel 31, and a cam 32.

At the bottom of the member 22 a rearwardly projecting lug 22C is formed and this lug is bored for the passage of a vertical stem 33 which holds a cushioning spring 33A in position.

34 is a spring barrel containing a clock spring 35 whereof one extremity is anchored

to the arbor 30 and the other to the barrel 34 which is fixed.

36 is a latch or detent pivoted at 36A at the back of slide 28 and adapted to engage with the cam 32, the free end of the latch or detent 36 being attached to the end of a wire control 37 of which the flexible casing 38 terminates in a nipple 38A secured to a lug 39 on the rear of slide 28, the opposite end of the casing terminating in a nipple 38B fitting into a lug 40 at the upper part of the end-stand or frame end 4, while the corresponding end of the wire or cable 37 is secured to a lever 41 pivoted by stud 42 to a bracket 43 attached to the frame end 4 and supporting the casing 44 of the delivery regulator.

This delivery regulator, which is illustrated in Figures 5 and 6 of the drawings, is constructed in the following manner.

The bracket 43 supporting the casing 44 is bolted to the end-stand 4 and 45 is the end roller stand which is mounted on the roller stand beam 46 as usual.

The front roller spindle 2 passes through the frame end 1 against the inner face of which the end boss 47 abuts, this extension 2A of the front roller spindle being mounted in a suitable bearing and projecting into the casing 44.

Upon said extension 2A of the front roller spindle is formed or keyed a worm 48 which meshes with a worm wheel 49 carried by an arbor 50 rotating in a bearing 51 integral with the casing 44, said arbor 50 being slidable axially within said bearing against a coiled return spring 52. A wrist-pin 53 is fixed in said worm wheel 49 and in rotation of the worm wheel said wrist pin is adapted to strike the upper or free end 41A of the lever 41 pivoted on stud 42 to the bracket 43. The periphery of worm wheel 49 is gapped or recessed at 49A.

Loosely mounted on said arbor 50 near the outer end thereof is a disc 54 whereof the face is engraved or graduated from 0 to 10 yards, said disc being apertured at 54A to engage a pin 55 accommodated in an aperture in the bracket 43. A pointer 56 movable over the face of disc 54 is mounted on the reduced end 50A of arbor 50 which end terminates in a screw-threaded portion on which is screwed the knurled nut 57 serving to clamp the pointer 56 in any selected angular position.

The delivery regulator is set, prior to bunch building, according to the desired length of yarn which is required to be wrapped on the bunch, by the operator pulling arbor 50 axially outwards by means of the knurled nut 57 until the worm wheel 49 disengages from the worm 48 and then rotating the arbor until the pointer 56 is opposite the required figure on the face of the disc 54, whereupon, on releasing the nut 57, the arbor and worm-wheel are returned into working position by

the spring 52. The pin 55 prevents rotation of the disc 54 while the aforesaid adjustment is being made.

The frame is then started up and the worm wheel 49 is rotated until the wrist pin 53 trips the extension 41A of lever 41 and moves lever 41 angularly, and thus through the cable 37 actuates the latch or detent 36 when the predetermined number of yards of yarn for the bunch have been delivered by the front rollers. The worm wheel 49 continues to rotate a little further and is brought to rest by the gap 49A disengaging it from the worm 48.

Still referring to the application of the invention to a ring spinning frame, and assuming that empty bobbins have been placed upon the spindles 8 and the ring rail 7 has been brought to the starting position by means of the usual handwheel 18D, preparation for building the bunch is made first by setting the delivery regulator as just described, and then by rotating the handwheel 31 so as to cause the pinion 24 through rack 23 to lower the slide or rod end iron proper 22 until by the rotation of the cam 32 the latch or detent 36 engages with the nose thereof when the bunch building roller 10 on the chain rod 9 will be in contact with the slotted lever 11 as shown in Figure 1.

The frame is then set in motion through the usual means and, through cam 14 the short lever 13 of the builder motion is oscillated and with it the extension 13A located above the pivotal axis 13B of the lever which has the slotted connection with the lever 11.

The arrangement of this linkage is such that a shorter pick than is normally the case is imparted to the chain rod 9, this length of pick being half an inch for the duration of bunch building.

When the predetermined length of yarn has been wrapped on to the bunch, the above described delivery regulator functions automatically, as already explained, to withdraw the latch or detent 36 from engagement with the nose of the cam 32, thus enabling the clock spring 35 (now in a state of compression) to rotate the pinion 24 and through rack 23 to elevate the slide or rod end iron proper 22 and cause the tapered surface 22A thereof to come into contact with the supplementary roller 20 on chain rod 9 and to move the latter longitudinally into the spinning position as soon as the parallel face of slide 22 engages roller 20, and remove the roller 10 from contact with the lever 11, as shown in Figure 3. The cushioning spring 33A supplements the effort of the clock spring 35 in raising the parts.

The whole of the rod end iron assembly now reciprocates and conveys motion from the cam 14 to the roller 20 thus imparting the normal pick to the chain rod 9 for the duration of the spool building.

Referring now to Figures 7, 8, 9 and 10.

The spindles 8A are fitted with caps 8B and the lifter rail 7B is carried by the lifter spindles 7C. The short lever 13 of the builder motion is of normal construction, that is to say, it is not extended upwardly above its pivotal axis as in the case of a ring frame, nor does it carry a slotted lever, but the equivalent of the lever 11 is constituted by the bent lever 58 mounted pivotally at 58A upon a vertically slidable rack member 59, said lever 58 carrying a roller 60 which is adapted to engage a stationary inclined stop plate 61 fixed to the spindle rail 6.

The chain rod 9 has a plate 62 bolted at 62A, 62A, to it, which plate is formed integrally with a boss 62B holding a pin 62C passing through a fixed guide eye 62D to prevent tilting of the chain rod 9.

Said plate 62 is also formed integrally with a rounded lug 63 (the equivalent of the aforesaid roller 10) and with a second rounded lug 64 (the equivalent of the roller 20); the lug 63 being contacted with during bunch building by the bent lever 58, and the lug 64 being contacted with during spool building by an adjustable stop 65 taking into a lug 65A formed on the slide or rod end iron 66.

The rack slide 59 is carried by the rod end iron 66 which is formed integrally with two lugs 66A, 66A, supporting a stationary vertical rod 67 on which the slide 59 is mounted by means of a boss 59A. The rod end iron 66 is also formed with bearing bosses 66B and 66C, the former boss 66B for a spindle 68 on the forward or outer end of which is a handwheel 69, and the latter boss 66C for an arbor 70 which extends through the part 66 and has keyed on its inner end a gear wheel 71 meshing with a pinion 72 keyed on the inner end of the spindle 68. On the outer or forward end of the arbor 70 is secured one end of the clock spring 35 whereof the outer end is secured to a pin 35A held in two ears 66D, 66D, integral with the bearing boss 66B. Near the centre of its length the arbor 70 also has keyed on it a pinion 70A which engages the rack slide 59.

The gear wheel 71 is integral with a cam 73 with which engages a latch or detent 74 pivoted at 74A and having attached to it the control wire or cable 37 connecting it with the delivery regulator as in the previous construction.

In the embodiment of the invention, just described, as applicable to a cap or a flyer frame, preparation for building the bunch is made first by setting the delivery regulator in the manner explained with reference to Figures 5 and 6. The handwheel 69 is then rotated and, by means of gearing 70A, 71 and 72 the rack slide 59 is raised until the roller 60 has contacted with and ridden over the inclined surface of stop 130

plate 61 into the position it is shown to have reached in Figure 7. By this elevation of rack slide 59 the cam 73 is caused to rotate and to secure engagement with the latch or 5 detent 74, and the lower portion of the bent lever 58 is brought into contact with the bunch building lug 63, the forwardly projecting or upper portion of the lever 58 having first contacted with the lug 63 and pushed 10 the chain rod longitudinally to the right, the lug 64 being clear of the adjustable stop 65.

The frame is then set in motion and by 15 the reciprocation of the rod end iron 66 (through the normal operation of the builder motion) the pick reducing lever 58 is oscillated and imparts through lug 63 the requisite short pick to the chain rod 9 for the duration of the bunch building.

When the requisite length of yarn (previously set up on the disc 54) has been wrapped on to the bunch, the delivery regulator operates, exactly as before, to withdraw the latch or detent 74 from engagement with the cam 73 whereupon the spring 35 actuates pinion 70A and causes the rack slide 59 to descend into the position shown in Figure 9 wherein the nose of the bent lever 58 has been withdrawn from contact with the bunch building lug 63 and, owing to the weight of the lifter rail and associated parts, the chain rod has received longitudinal movement to the left by an amount sufficient to bring the spool building lug 64 into contact with the stop 65 carried by the rod end iron 66, whereupon spool building continues in the normal manner until the spools or bobbins are completed.

During the normal building of the spools the rod end iron 66 is moved, by the builder motion, the full travel of say, two inches, but during bunch building this extent of travel becomes reduced to, say, half an inch, by reason of the roller 60 becoming the fulcrum of the lever 58 which thereby functions in a manner analogous to the lever 11 of Figure 1.

It is to be observed that in Figure 1 of the drawings the builder motion cam is shown as having come to rest with a re-entrant portion in contact with the roller on the short lever. If however the cam had come to rest with a salient portion or peak in contact with the roller, the position of the ring rail would be higher than that illustrated. Conversely, in Figure 7 of the drawings, the builder motion cam has come to rest with the salient or peak in contact with the roller on the short lever, but if it had stopped with the re-entrant engaging the roller the lifter rail would have been positioned lower than as illustrated in Figure 7.

It is, however, immaterial whether when the frame is stopped the builder motion cam is in the position illustrated, or that just referred to, or in any intermediate position, the

bunch is correctly located irrespective of the position in which the lifter motion comes to rest.

It therefore becomes manifest that, by the two constructional forms of the invention just described, the position of the bunch on the spool is definitely determined, the amount of yarn wrapped on to the bunch is positively regulated to a predetermined length, and for bunch building the normal pick is reduced for the duration of the bunch and, on completion of the bunch, is automatically converted into the normal pick requisite for spool building.

What I claim is:—

1. In a spinning or analogous machine having a bunch builder motion giving a short traverse to the bunch and after a predetermined time shifting to a long traverse for winding the spool, a builder motion cam, a lifter motion, devices operable when the machine is stopped to break operative connection between said builder motion cam and said lifter motion whereby to ensure that the bunch is built at the base of each spool irrespective of the angular position in which said builder motion cam comes to rest, a linkage to convert the standard pick of the builder motion to the short pick requisite for building said bunch, automatically, for the full period of the bunch building operation, and delivery regulating mechanism whereby a selected predetermined length of yarn, unaltered by any change in counts or in the speed of the lifter motion, is automatically delivered and wrapped on to the bunch.

2. In a spinning or analogous machine of the kind referred to, having a builder motion including a builder motion cam and a rod end iron and also having front rollers and a chain rod, means to disconnect the builder motion cam from the chain rod when the machine is stopped, a pick-reducing linkage between the builder motion and the chain rod, a manually-set automatically operating delivery regulator co-operating actuating with the front rollers of the machine and a spring motor associated operatively with the rod end iron assembly and controlled by said delivery regulator; for the purposes set forth.

3. In a spinning or analogous machine as claimed in claim 2, an abutment on the chain rod co-operating with the pick-reducing linkage, means for imparting the normal pick, and a second abutment on said chain rod said second abutment cooperating with said means for imparting the normal pick.

4. A builder motion for spinning and analogous machines of the kind referred to, embodying a rod end iron assembly including a vertically slideable rack member associated with a pivoted pick-reducing lever, a chain rod, an abutment appropriate to said pick-reducing lever on the chain rod, means to

move said rack member in a vertical direction to engage said pick-reducing lever with its abutment, a second abutment on the chain rod engageable with the rod end iron, means to move said rack member automatically in a vertical direction at the required time to bring said rod end iron into engagement with its appropriate abutment on the chain rod, and automatically operating means connected with the front rollers of the machine for controlling the actuation of the means which

move said rack member automatically in a vertical direction.

5. In a builder motion as claimed in claim 4, a spring motor to move the rod end iron assembly from the bunch building position 70 into the spool building position, and a delivery regulator connected by a cam and detent to said spring motor and automatically controlling the actuation of the motor on the conclusion of the bunch building operation. 75
